(57) **CLAIM**

The ornamental design for an electric scooter, as shown and described.

DESCRIPTION

FIG. 1 is a front perspective view of an electric scooter showing the design.

FIG. 2 is a right side elevation view of the electric scooter showing the design.

FIG. 3 is a left side elevation view of the electric scooter showing the design.

FIG. 4 is a front elevation view of the electric scooter showing the design.

FIG. 5 is a rear elevation view of the electric scooter showing the design.

FIG. 6 is a top plan view of the electric scooter showing the design; and,

FIG. 7 is a bottom plan view of the electric scooter showing the design.

The portions of the electric scooter shown in broken lines form no part of the claimed design. The broken lines in FIG. 7 adjacent the solid lines showing the body and the front fender of the electric scooter indicate that the bottom of the surfaces within those broken lines form no part of the claimed design.
